(57) **CLAIM**

The ornamental design for an expandable keyboard, as shown and described.

DESCRIPTION

FIG. 1 is a top-right perspective view of an expandable keyboard in an open configuration, where holders are in an upright position;

FIG. 2 is a top-right perspective view in a closed configuration;

FIG. 3 is a top view in an open configuration, where holders are in an upright position;

FIG. 4 is a top view in a closed configuration;

FIG. 5 is a right-side view in an open configuration, where holders are in a collapsed position;

FIG. 6 is a left-side view in an open configuration;

FIG. 7 is a front view in an open configuration, where holders are in a collapsed position;

FIG. 8 is a bottom-left perspective view in an open configuration;

FIG. 9 is a back view in an open configuration; and,

FIG. 10 is a back view in an open configuration.

The broken lines in the drawings illustrate portions of an expandable keyboard which form no part of the claimed design.
